UNITED STATES PATENT OFFICE.

ANDREW W. REYNOLDS, OF FITZGERALD, GEORGIA.

DESIGN FOR A NUT-LOCK WASHER.

SPECIFICATION forming part of Design No. 32,217, dated February 13, 1900.

Application filed January 18, 1900. Serial No. 1,943. Term of patent 14 years.

To all whom it may concern:

Be it known that I, ANDREW W. REYNOLDS, a citizen of the United States, residing at Fitzgerald, in the county of Irwin and State of Georgia, have invented and produced a certain new and original Design for Nut-Lock Washers; and I do declare the following to be a full, clear, and exact description of the invention, such as will enable others skilled in the art to which it appertains to make and use the same.

The invention relates to a new and original design for nut-lock washers; and it consists of a design of the shape and configuration shown in the accompanying drawings, in which--

Figure 1 is a perspective view. Fig. 2 is a rear elevation.

The leading feature of the design comprises

the body portion 1, having a horizontal lower edge 2, parallel vertical sides 3, inclined corners 4, and a horizontal upper edge 5 parallel with the lower edge, and radial curved wings 6, projecting from the inclined corners and the horizontal top and of less thickness than the body portion. 25

What I claim is--

The design for a nut-lock washer, substantially as herein shown and described.

In testimony whereof I have hereunto set my hand in presence of two subscribing witnesses. 30

ANDREW W. REYNOLDS.
